UNITED STATES PATENT OFFICE.

ALFRED VINCENT KEMP, OF LONDON, ENGLAND.

REVERSIBLE REGENERATIVE FURNACE.

Application filed October 12, 1923. Serial No. 668,133.

To all whom it may concern:

Be it known that I, ALFRED VINCENT KEMP, a subject of the King of Great Britain, residing at 36-38 Kingsway, in the county of London, England, have invented new and useful Improvements in Reversible Regenerative Furnaces, of which the following is a specification.

This invention relates to reversible regenerative open-hearth furnaces and has for its object to provide, at each end of the furnace, distinct, or separate, and reversible, structures for conveying the heated air and gases from the regenerators, to such furnaces and for conveying the products of combustion from the said furnaces to the downtakes of the regenerators, as hereinafter explained.

According to this invention, at each end of the furnace there are provided two distinct and separate structures, which are termed blocks, one block at each end containing air and gas ports for conveying the air and gas from the regenerators into the furnace and the other block at each end containing a port, or ports, for conveying the products of combustion from the furnace to the downtakes of the regenerators. At each end of the furnace, the said blocks are either independently, or jointly, movable, so that, (when the furnace is in operation) at one end the block containing the air and gas ports is in position to convey air and gas into the furnace, whilst at the other end the block containing the port, or ports, through which the products of combustion from the furnace pass is in position over the downtakes of the regenerators, the other blocks, at the respective ends of the furnace, being in their inoperative positions. When the direction of the flow of the gases through the furnace is to be reversed the blocks at each end of the furnace are moved, so that the blocks which were before in their inoperative positions, are brought into their operative positions and the blocks which were before in their operative positions are brought into their inoperative positions.

The blocks at each end of the furnace are mounted on a carriage, or the equivalent, whereby they can be conveniently moved to the required positions and they are preferably so disposed that the either block which for the time being is in its inoperative position can, if desired, be removed from the carriage, or the like, and be replaced by an

other block, thus obviating the necessity for stopping the furnace in case, for instance, of a block requiring repair.

The accompanying drawings illustrate a construction in accordance with this invention shewing how it may be carried into effect, but it is to be understood that the invention is not limited to the precise details illustrated.

Figure 1 is a longitudinal section shewing the two ends of an open-hearth furnace, but with the mid-part omitted. Figure 2 is a plan (partly in section) of Figure 1 and Figure 3 is a vertical section on the line *x*, *x*, Figure 2. The aforesaid blocks at one end of the furnace are marked, that for the gas and air *A*, and that for the exhaust gases *B* and at the other end of the furnace the corresponding blocks are marked *A*² and *B*² respectively.

With the parts in the positions shewn in the drawings, gas passes from the gas regenerator by way of the up-take 1 to the port 2 at the exit of which it meets, at 4, the air which passes from the air regenerator, by way of the uptake 3, and, at the place where the said gas and air meet, combustion takes place and the products of combustion pass along the furnace to the exit port 5, and into the block *B*² at the other end, where a portion goes down by the downturn 6, to heat the air regenerator, the other portion going down by the downturn 7 to heat the gas regenerator.

The gas port at 2 may be made of any suitable material, for instance, of cast steel, mild steel, cast iron or other suitable material. The said gas port is shewn as being jacketed and cooled by water, circulating by means of pipes *a* *a*².

In the drawing the blocks *A* and *B*² are shewn in the positions in which the heated gas and air are entering the furnace, from the regenerators at the left-hand end of the furnace and the exhaust gases are passing to the regenerators at the right-hand end of the furnace, the block *B* (for exhaust at the left-hand end) and the block *A*² (for admission of gas and air at the right-hand end) being in their inoperative positions.

When the furnace is reversed the blocks *A* and *B*² which, in the drawings, are shewn in their operative positions are moved into their inoperative position and the blocks *B* and *A*² which, in the drawing,

are shewn in their inoperative position are moved into their operative position.

These movements, in the construction illustrated, are shewn as being effected by mounting the pair of blocks, at each end of the furnace, upon a carriage C, which can run on rails d, on a frame D, arranged at right angles to the length of the furnace these rails having turned-up ends d² constituting stops, the said frame being pivoted at d³ and the carriage C being traversed by the plunger of the hydraulic cylinder E, centred at e, to follow the lifting movement of the frame D, upon its fulcrum d³, effected by the plunger of the hydraulic cylinder F, for lifting the dippers g clear of the trough part g², of the seal to allow of the traversing movements of the carriage. At the end of each movement of the carriage C the hydraulic cylinder F, allows the frame D to descend and the dipper g, of the block which has then been brought into position, to enter the trough-part g² of the seal. It will be seen that the block for the time being out of operation can be readily repaired, and if required removed and replaced without stopping the furnace.

The described means of effecting the required movements are considered most convenient, but any other suitable means may be used.

In the arrangement described the structures containing the air and gas inlet ports are not exposed to the action of the intensely hot outgoing gases and they therefore retain their shape and original port proportions and ensure proper flame control and rapid heating and melting of the charges. By providing separate structures, such as are herein termed blocks, respectively for the ingoing air and gases and for the products of combustion, each structure can, of course, be designed independently for its particular purpose and the correct proportions be given to each structure, so that high velocity can be obtained at the end of the furnace which for the time being is the ingoing end whilst low velocity

can be obtained at the end of the said furnace which for the time being is the outgoing end and the best conditions for the ingoing air and gases can be arranged absolutely independently of the best conditions necessary for the outgoing products of combustion passing from the furnace to the downtakes of the regenerators, the ingoing air and gases and the outgoing products of combustion being distinctly and separately controllable by suitably proportioning the ports in the respective structures and practically even heating of the hearth, from end to end of the furnace, can be attained.

The improvements according to this invention can be readily applied to any existing, or known, type of reversible regenerative furnace, of the open hearth type.

What I claim is:—

1. In reversible regenerative open hearth furnaces, two distinctly separate structures at each end of the furnace, one structure containing the ports for the admission of the heated gas and air to the furnace, and the other containing the port for conveying the products of combustion to the regenerators, and means for reversing the positions of the said structures relatively to the passages communicating with the regenerators and the furnace hearth, substantially as described:

2. In a furnace according to claim 1, the means for reversing the positions of said structures including a carriage for each pair of structures such that the structures at each end of the furnace, can be moved into, and out of, operative position, and allow, whilst the furnace is in operation, of the removal and replacement of the structure which is in its inoperative position.

In testimony whereof I have signed my name to this specification in the presence of two subscribing witnesses.

ALFRED VINCENT KEMP.
